(57) **CLAIM**

The ornamental design for a gun grip, as shown and described.

DESCRIPTION

FIG. 1 is a front elevational view of a gun grip showing my new design;

FIG. 2 is an enlarged elevational view of the ornamented gun grip;

FIG. 3 is an enlarged rear elevational view thereof;

FIG. 4 is a left edge view thereof;

FIG. 5 is a right edge view thereof;

FIG. 6 is a top plan view thereof; and,

FIG. 7 is a bottom plan view thereof.

The portions shown in broken lines in FIGS. 1, 2 and 3 are for information only, and form no part of the claimed design.
